UNITED STATES PATENT OFFICE

102,651

DESIGN FOR A SLIPPER

Moe Jacob, New York, N. Y.

Application January 20, 1936, Serial No. 60,681

Term of patent 3½ years

To all whom it may concern:

Be it known that I, Moe Jacob, a citizen of the United States and resident of New York city in the county of New York and State of New York, have invented a new, original, and ornamental Design for a Slipper, of which the following is a specification, reference being had to the accompanying drawing, forming part thereof, in which,

Fig. 1 is a plan view of the slipper showing my new design; and

Fig. 2 is a side view of the slipper shown in Fig. 1.

One important feature of the design resides in an arrangement wherein the vamp passes down inside the heel portion of the upper and the instep band is therefore not seen as extending down to the shank portion of the sole. Also, according to another important feature the lower edge of the ornamental band is curved and so arranged as to be substantially in a plane parallel to the surface on which the shoe stands.

I claim:

The ornamental design for a slipper, as shown and described.

MOE JACOB.
